CIRCUIT BREAKER

Richard C. Cunningham, East McKeesport, Pa.,
assignor to Westinghouse Electric Corporation,
East Pittsburgh, Pa., a corporation of Pennsylvania

Application September 15, 1941, Serial No. 410,870

25 Claims. (Cl. 175—294)

1

The invention relates to circuit breakers and, more particularly, to circuit breaker operating mechanisms of the type which are operable to produce closing or quick automatic reclosing of the circuit breaker.

Circuit breakers are frequently required for quick automatic reclosing service, and it is particularly desirable that such breakers embody an operating mechanism capable of rapidly reversing the switching movement of the breaker, in order to provide for quick automatic reclosing of the breaker immediately after interruption of the circuit and before the breaker reaches full open position so as to reduce the time the circuit is open as much as possible.

Rapid reversal of the switching movement of the circuit breaker for a quick reclosure, particularly in the case of a large circuit breaker, requires a much greater mechanism effort than is required for a normal closing operation when the closing movement of the breaker is started at a time when the breaker is at rest in the full open position. For example, a pneumatically operated mechanism having a combination of air pressure and operating piston diameter suitable for quick automatic reclosing and rapid reversal of switching movement would produce too much force for normal closing operations and may cause destructive slamming on normal closing operations. The same condition may also be present in the case of an electrically operated circuit breaker mechanism designed for quick automatic reclosing service.

An object of the invention is the provision of a circuit breaker embodying an operating mechanism operable to effect normal closing of the breaker and also operable to effect quick automatic reclosing operation of the breaker, the mechanism having means for automatically causing a greater closing force to be applied on quick automatic reclosing operations than on normal closing operations.

Another object of the invention is the provision of a circuit breaker embodying an operating mechanism operable to produce normal closing and also quick automatic reclosing of the breaker, with means for reducing the operating force on normal closing operations to prevent destructive slamming of the breaker.

Another object of the invention is the provision of a circuit breaker operating mechanism operable to rapidly reverse the switching movement of the breaker and automatically reclose the breaker after interruption of the circuit and before the breaker reaches full open position, and

also operable to produce normal closing of the breaker from the full open position, the mechanism having automatically selective means for reducing the operating force on normal closing operations.

Another object of the invention is the provision of a circuit breaker embodying an operating mechanism which is pneumatically operated to produce normal closing of the breaker, and 10 also operated to produce quick automatic reclosing of the breaker by rapidly reversing the switching movement, the mechanism being provided with an automatically selective throttle for reducing the air pressure applied to the operating 15 piston on normal closing operations.

Another object of the invention is the provision of a circuit breaker embodying an operating mechanism which is pneumatically operable to quickly reverse the switching movement of the 20 breaker and quickly automatically reclose the breaker after interruption of the circuit but before the breaker reaches full open position, and which is also pneumatically operable to produce normal closing of the breaker from the full open 25 position, the mechanism being provided with an automatically selective throttle comprising a throttle valve which automatically reduces the air pressure applied to the operating piston on normal closing operations and permits full air 30 pressure to be applied to the piston on quick automatic reclosing operations.

Another object of the invention is the provision of a circuit breaker operating mechanism operated by compressed air to produce normal closing, or quick automatic reclosing of the breaker with rapid reversal of switching movement of the breaker, the mechanism having an automatically selective throttle valve responsive to the position of the operating piston to reduce the air pressure applied to the piston on normal closing operations and to cause full air pressure 40 to be applied to the piston on quick reclosing operations.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawings, in which:

Figure 1 is a vertical sectional view of a circuit breaker operating mechanism of the pneumatic type embodying the features of the invention,

the mechanism being shown in the closed position in which the circuit breaker is closed;

Fig. 2 is a fragmentary sectional view taken substantially on the line II-II of Fig. 1 showing the main exhaust valve and its connection to the operating cylinder and to the exhaust pilot valve, the main exhaust valve not being visible in the section of Fig. 1 because it is disposed in front of the plane of the section of Fig. 1;

Fig. 3 is a wiring diagram of the electrical control circuits for the circuit breaker operating mechanism, the circuit breaker and its operating mechanism being shown schematically in this figure; and

Fig. 4 is an enlarged fragmentary sectional view of the mechanism showing the parts in an instantaneous position during the beginning of a normal closing operation of the breaker, the throttle valve having been automatically operated to throttling position.

The invention is illustrated as applied to a circuit breaker operating mechanism of the pneumatic type similar to that disclosed in the co-pending application of James M. Cumming and Richard C. Cunningham, Serial No. 410,686, filed September 13, 1941, and assigned to the assignee of the present invention.

Referring to the drawings, the circuit breaker 1 shown schematically in Fig. 3, may be of any conventional construction either of the oil break, air break or gas blast type. The circuit breaker, as shown, comprises stationary contact means 9 and cooperating movable contact means 11 for controlling a main circuit represented diagrammatically by a single line 13. Although illustrated as a single pole circuit breaker, it will, of course, be understood that the breaker may be a multi-pole circuit breaker having a set of contact means 9-11 for each pole thereof with the movable contact means mechanically connected for simultaneous operation in the usual manner. The circuit breaker is biased to open circuit position by means of an accelerating spring shown schematically at 15, and the breaker is mechanically connected to the operating mechanism indicated generally at 17 by suitable connecting means. The connecting means is represented schematically as comprising a lever 19 pivoted at 21 on a fixed support, one end of the lever being pivotally connected to the breaker lift rod 23 and the other end being pivotally connected to the breaker operating rod 25 which is, in turn, mechanically connected to the operating mechanism 17.

Referring now to Fig. 1, the operating mechanism comprises a main casting 27 which is formed to provide a cylinder 29 closed at the upper end by an integral part of the casting. A closure member 31 is secured to the lower end of the cylinder 29 to close this end of the cylinder, and this closure member has a relatively large port 33 therein which is open to the atmosphere. An operating lever or latching lever 35 is pivotally mounted at one end on the casting 27. The lever 35 consists of two spaced parallel levers 37 (only one being visible in Fig. 1) which are pivotally connected at one end by means of a pivot pin 39 to the upper end of a pair of parallel links 41 (only one appearing in Fig. 1) which are in turn pivotally mounted on an ear 43 of the main casting 27 by means of a pivot pin 44. The opposite end of the levers 37 comprising the operating lever 35 are connected by a cross member and carry a short shaft 45 which rotatably supports a roller 47 disposed between the parallel levers 37

37. The breaker operating rod 25 is pivotally connected by a pivot pin 49 to an intermediate point of the operating lever 35, the pivot pin 49 extending transversely through the parallel levers 37 and engaging an opening in the lower end of the rod 25 which is disposed between the parallel levers, the breaker lever 35 is adapted to be held in the closed position shown in Fig. 1 to hold the breaker closed by means of a high speed latching mechanism comprising a main latch 51 which is pivoted on the main casting 27 by means of a pivot pin 53. The latch 51 is adapted to extend between the parallel levers 37 and its latch end is adapted to engage and restrain the roller 47 carried by the free end of the breaker lever 35. The latch 51 is biased to latching position against a stop 55 by means of a spring pressed plunger 57 which engages a projection 59 of the latch. The plunger 57 is slidably mounted in an opening in a portion of the main casting 27 and is biased inwardly against the projection 59 of the latch 51 by means of a compression spring 61 surrounding the plunger 57 and disposed between the head thereof and a plate 63 secured to the casting 27. An adjustable nut 65 is threaded on the outer end of the spring pressed plunger 57 and this nut serves to limit inward movement of the plunger.

The construction of the latch face of the main latch 51 is such that this latch alone will not serve by itself to hold the breaker operating lever 35 in closed position unless the main latch is itself held in latching position. An auxiliary latch 67 is provided for normally engaging and holding the main latch 51 in latching position. The auxiliary latch 67 is pivoted on the casting 27 by means of a pivot pin 69 and has a latch projection 71 which is adapted to engage under a tail projection 73 of the main latch 51 in the latching position of the latching means. The auxiliary latch 67 is biased to latching position, as shown in Fig. 1, by a compression spring 75 which is seated in a recess in the casting 27 and engages an integral projection of the auxiliary latch. The auxiliary latch 67 is also provided with a projection 77 which extends directly over the upper end of the trip plunger 79 of an electro-magnetic trip device 81. The trip device 81 comprises in addition to the trip plunger 79, an E-shaped core 83 of magnetic material mounted on the casting 27, an energizing winding 85 which is mounted on the center leg of the E-shaped core, and a movable armature 87 cooperating with the core 83. The trip plunger 79 is secured to the center portion of the armature 87 and slidably extends upwardly through a guide opening in the center portion of the core 83 and through an opening in the horizontal portion of the main casting 27. The armature 87 is biased downwardly to unattracted position, as shown in Fig. 1, by a compression spring 89 which encircles the upper portion of the plunger 79 and is disposed between a collar 91 secured to the plunger and a bushing 93 which is threaded in the upper end of the plunger through which the plunger extends. When the trip device 81 is energized, the armature 87 thereof is moved upwardly against the core 83 causing upward movement of the trip plunger 79. This upward movement of the trip plunger causes the auxiliary latch 71 to be rotated counterclockwise and disengage the projection 73 of the main latch 51, whereupon the accelerating spring 15 of the circuit breaker moves the breaker to open circuit position, the operating lever 35 being rotated counterclockwise about its pivoted end by the opening movement of the

breaker. During the initial opening movement of the operating lever 35, the roller 41 forces the main latch 51 in a counterclockwise direction as it clears the latch. In order to prevent the auxiliary latch from being returned to latching position until the breaker operating lever 35 is returned to closed position there is provided a U shaped holding lever 95 the legs of which are pivotally mounted on the ends of pivot pin 69, on opposite sides of the auxiliary latch 67. The holding lever 95 is biased in a counterclockwise direction by the compression spring 97 which is seated in a recess in the casting 27 and engages a projection 99 of the holding lever. The cross member on the free end of the holding lever 95 is disposed directly beneath the end of the operating lever 35 so that the holding lever is held in inoperative position when the operating lever 35 is in closed position. However, when the operating lever is released and moves toward open position, the holding lever 95 is rotated in a counterclockwise direction and a lateral projection 101 of the portion 99 thereof engages and holds the auxiliary latch 67 in unlatched position until the breaker operating lever 35 is returned to closed position and its roller 41 has become reengaged by the latch face of the main latch 51. For this purpose the biasing spring 97 of the holding lever is of greater strength than the auxiliary latch biasing spring 75.

An operating piston 103 having piston rings 105 is movable within the operating cylinder 29 and this piston has a piston rod 107 which slidably extends in a fluid tight manner through an opening provided therefor in the top wall of the cylinder 29. The upper end of the piston rod 107 has a connecting element 109 threadedly connected thereto, which is pivotally connected to the pivot pin 49 carried by the operating lever 35. Thus the operating piston 103 is mechanically connected to the circuit breaker operating rod 25 and operating lever 35. The purpose of the lever 35 is to provide a mechanical advantage for the latching means to reduce the latch load, otherwise the lever 35 could be omitted and the latch arranged to latch directly on the operating rod. The operating piston 103 is adapted to be moved downwardly in the cylinder 29 to close or automatically reclose the circuit breaker, by compressed air from an auxiliary air reservoir or tank 111, the compressed air being admitted to the upper end of the operating cylinder 29 through an inlet passage controlled by a main inlet valve indicated generally at 113. The opening operation of the main inlet valve is, in turn, controlled by a pilot valve 115 operated by an electromagnet 117.

The main inlet valve 113 comprises a valve housing 119 which is secured to the side of the main cylinder casting 27 by a plurality of bolts (not shown), and this valve housing is provided with inlet passages 121 and 123, the former communicating with the auxiliary air reservoir 111 and the latter communicating with an inlet port 125 in the upper end of the main cylinder 29. A main valve element 127 disposed in the valve housing has a stem 129 slidably mounted in a guide sleeve 131 which is carried by a bushing 133. The bushing 133 is threaded in an opening in the valve housing between the passages 121 and 123, and this bushing serves as a valve seat for the valve element 127. The guide sleeve 131 is connected to the bushing 133 by a plurality of spider legs which permit the compressed air to flow through the passages 121 and 123 when the valve is open. The valve element 127 is

biased to closed position, as shown in Fig. 1, by means of a helical compression spring 135 which surrounds the guide sleeve 131. The lower end of the valve biasing spring 135 bears against the spider legs of the bushing 133 and the upper end of the spring bears against a spring support 137 which is secured to the upper end of the valve stem 129.

The auxiliary air tank 111 is secured to the underside of the valve housing 119 by means of a plurality of bolts 139 (only one being shown) which extend through the valve housing 119 and engage an annular flange 141 formed on the neck of the air tank 111, thereby clamping the flange tightly against the underside of the valve housing 119. A sealing ring 143 is interposed between the valve housing and the flange 141 of the auxiliary air tank 111 to tightly seal the joint therebetween. The auxiliary air tank 111 is connected to a main air storage tank (not shown) by means of a conduit 145, compressed air being supplied to, and maintained in, the main storage tank by a suitable motor driven compressor unit, not shown.

The main inlet valve 127 is adapted to be opened by means of a valve piston 147 to admit compressed air into the upper end of the operating cylinder 29 to close or automatically reclose the circuit breaker. The valve piston 147 is movable in a valve cylinder 149 formed in the valve housing 119, and the valve piston is biased upwardly to an inoperative position against the head of the valve cylinder by means of a helical compression spring 151 which surrounds a portion of the valve biasing spring and is disposed between the underside of the valve piston and a shoulder formed in the valve housing 119.

The valve operating piston 147 is adapted to be moved downwardly to open the main inlet valve, by compressed air from the auxiliary air tank 111, through passages 152 and 153 formed in the valve housing 119, the valve piston 147 being suitably recessed at its upper end, as shown in Fig. 1, for the purpose of permitting the compressed air to move the piston downwardly from its upper inoperative position. The air passages 152 and 153 communicate with cooperating passages in the pilot valve housing 155 which is secured to the main valve housing 119. Communication between the auxiliary air tank and the upper end of the valve cylinder 149 is normally shut off, however, by a pilot valve 157 disposed in the pilot valve housing 155. The pilot valve 157 is biased to closed position against its seat by a compression spring 159 which bears against the underside of the pilot valve. The pilot valve is adapted to be operated to open position to cause air pressure to open the main inlet valve, by means of the electromagnet 117 upon energization thereof.

The cylinder portion 149 of the main inlet valve housing is provided with a plurality of ports 150 (only one being shown) adjacent the lower end of the operating cylinder 149 which open to the atmosphere. These ports function to prevent the main inlet valve from being reclosed by the differential pressure on the under side of the valve piston 147 aided by the force of the springs 135 and 151, as the main inlet valve 127 opens. A skirt on the lower end of the valve piston 147 closes the ports 150 as the piston reaches the lower end of its stroke thereby preventing any further leakage of the closing air through the ports 150. The ports 150 also function to slowly exhaust the air pressure in the main operating

cylinder 29 after the completion of a normal closing operation.

The electromagnet 117 comprises a frame 161 and a core 163 both of magnetic material, an energizing winding 185, and a pivoted armature 167. The electromagnet is secured to the pilot valve housing 185 by the lower end of the core 163 being threaded into an opening in the upper end of the pilot valve housing 185, thus clamping the winding spool and the frame 161 to the pilot valve housing 185, the upper end of the core 163 having a shoulder which bears against a plate 169 which rests on the upper end of the winding spool. The armature 167 of the electromagnet is pivotally supported on the upper end of the frame 161, and this armature engages a plunger 171 which extends slidably through an opening in the center of the core 163, and the plunger is connected at its lower end to the pilot valve 157. The pilot valve biasing spring 159 normally maintains the pilot valve in closed position and the armature 167 in unattracted position. A casing 173 is secured to the plate 169 and frame 161, for enclosing the armature 167.

When the electromagnet 117 is energized, the armature 167 thereof is moved to attracted position depressing the plunger 171 and thereby causing opening of the pilot valve 157 to admit compressed air from the air tank 111 to the upper end of the valve cylinder 149. The compressed air flowing into the upper end of the valve cylinder through the passages 151 and 153 forces the valve piston 147 downwardly, thereby causing opening of the main inlet valve 127 to admit compressed air to the upper end of the breaker operating cylinder 29. When the main inlet valve 127 is open, compressed air flows from the auxiliary air tank 111, through the passages 121 and 123 into the main operating cylinder 29 and quickly moves the operating piston 103 downwardly to closed position, thereby closing the circuit breaker 7. As soon as the electromagnet 117 is deenergized, the pilot valve 157 immediately closes and the main inlet valve 127 is quickly returned by its biasing spring 135 to closed position, the valve operating piston 147 being also returned upwardly to its upper inoperative position by the spring 151.

A push button 175 extends through the casing 173 of the electromagnet 117 and engages the armature 167. The push button 175 serves as a means for manually opening the pilot valve 157 to cause a closing operation of the circuit breaker. The electromagnet 117 of the pilot valve 115 is adapted to be operated electrically to cause closing or automatic reclosing of the circuit breaker by circuit means which will be hereinafter described.

In order to provide for quick reversal of movement of the operating piston 103 and circuit breaker 7 to provide the effect of trip free operation of the circuit breaker and to also provide for quick reclosing of the breaker, the operating cylinder 29 is provided with an air pressure exhaust means for causing quick collapse of air pressure in the cylinder 29 whenever the tripping device 81 is operated, the exhaust passage of the exhaust means being so located that it is closed by the main operating piston before the piston reaches a position at which compressed air is admitted for quick reclosure. The pressure exhaust means comprises exhaust ports 181 formed in the side wall of the operating cylinder, indicated by the dotted lines of Fig. 1. Referring to Fig. 2, the exhaust ports 181 in the side of the

main operating cylinder 29 communicate with an exhaust passage 183 formed in the valve housing 185 of a main exhaust valve indicated generally at 187 (Fig. 2). The main exhaust valve housing 185 is secured to the side of the operating cylinder 29 by a plurality of bolts not shown, and the exhaust passage 183 extends through the valve housing and is open to the atmosphere at a port 188 on one side of the valve housing 185. The exhaust passage 183, however, is normally closed by a piston type exhaust valve 189 which is slidably mounted in a cylinder 191 formed in the exhaust valve housing 185. The piston type exhaust valve 189 is biased upwardly to closed position in which it closes the exhaust passage 183, by means of a helical compression spring 193 disposed within the valve cylinder. The upper end of the biasing spring 193 bears against the underside of the top of the piston valve 189 and the lower end of the spring bears against the bottom closure plate 195 of the valve cylinder 191. An annular guide projection 197 is formed integral with the bottom end plate 195 of the valve cylinder 191, and a cooperating cylindrical shaped projection 199 is formed on the inside of the piston 189. The projections 197 and 199 serve as a guide for the biasing spring 193, and when the exhaust valve is moved downwardly to open position, the cylindrical projection 199 slides into the annular projection 197 to provide a cushioning effect by the trapped air in the bottom of the annular projection 197 at the end of the opening movement of the exhaust valve 189. The exhaust ports 181 and exhaust passage 183 are of a size sufficient when the exhaust valve is open to cause quick collapse of air pressure in the main operating cylinder 29 even though the main inlet valve 127 may be open. The exhaust passage and exhaust valve operate to quickly dump the air pressure in the main operating cylinder 29 whenever the trip device 81 is operated, thus preventing any air pressure on the closing side of the main operating piston 103 from retarding opening movement of the circuit breaker when the circuit breaker is called upon to open. Opening of the main exhaust valve 189 is controlled by a pilot valve, indicated generally at 201, which is adapted to be operated by the trip device 81. Actual opening movement of the main exhaust valve 189 is produced by air pressure from the main operating cylinder 29, when the pilot valve is opened by the operation of the trip device 81.

The exhaust pilot valve comprises a light pilot valve element 203 movable in an opening 204 provided therefor in the pilot valve housing 205 which is formed integral with the main operating cylinder casting 27. The pilot valve element 203 is directly mechanically connected to the lower end of the trip plunger 79 which is connected to and extends through the armature 87 of the trip device. An air passage 207 formed in the main operating cylinder at one end and at the other end with the valve opening 204 in which the pilot valve element 203 slides. The valve opening 204 is in communication with a passage 211 (Fig. 2) formed in a closure plate 212 which is secured to the bottom of the pilot valve housing 205. A conduit 213 (Fig. 2) connects the air passage 211 to a recess 215 in the upper end of the exhaust valve cylinder 191 above the piston type main exhaust valve 189. The top of the main exhaust valve 189 is recessed, as shown in Fig. 2, to permit the air pressure admitted through the

conduit 213 when the pilot valve is opened to initiate opening movement of the main exhaust valve 189. As soon as the main exhaust valve 189 is opened a small distance by air pressure through the conduit 213, the air pressure flowing from the main operating cylinder 29, through the exhaust passage 183 passes over the top of the main exhaust valve 189 and the pressure quickly forces the main exhaust valve downwardly to open position and maintains it in open position against the force of the main exhaust valve spring 193 until the pressure in the main operating cylinder 29 has collapsed to a predetermined value whereupon the spring 193 immediately recloses the main exhaust valve. The air trapped in the annular projection 197 by the piston type projection 199 assists the spring 193 in quickly returning the main exhaust valve to closed position upon collapse of pressure in the breaker operating cylinder 29. The biasing spring 89 of the trip plunger 19 serves to return the exhaust pilot valve 203 to closed position as soon as the trip device 81 is deenergized.

A port 219 is provided in the lower end of the exhaust valve cylinder 191 to permit opening of the piston type main exhaust valve 189, the port 219 being opened to the atmosphere to allow air beneath the piston 189 to escape upon downward movement of the piston of the valve. One or more small bleeder openings 221 are provided in the top of the piston type main exhaust valve 189 to prevent any leakage air pressure from the pilot valve 201 and from the main cylinder 29 from falsely operating the exhaust valve 187.

The exhaust ports 181 are located in the side wall of the cylinder 29 at a predetermined point intermediate the end positions of the operating piston 103 so that these exhaust ports will be closed by the main operating piston 103 after the breaker has opened a predetermined distance sufficient to interrupt the circuit and before the main operating piston reaches the position at which compressed air is admitted for quick automatic reclosing of the breaker. This arrangement prevents the dumping of the quick reclosing air pressure and also allows a time interval for the mechanical closing of the main exhaust valve 189 on a quick reclosing operation of the mechanism. The closing of the exhaust ports 181 by the piston 103 also acts to provide a cushioning action for the partial opening stroke of the breaker and piston during a quick reclosing operation.

It will thus be seen that the pressure exhaust means in addition to providing trip free action to permit quick reversal of switching movement during closing or reclosing and substantially un retarded opening movement of the breaker, also provides for quick reversal of the opening movement during a quick reclosing operation by preventing the dumping of the reclosing air during the initial portion of the reclosing operation, before the exhaust valve 187 closes.

A pair of auxiliary switch devices 225 and 227 is mounted on a bracket 229 secured to the main casting 27. Each of these auxiliary switch devices comprises a multi-pole auxiliary switch of conventional construction, wherein the individual switch poles are adjustable relative to their operating shafts 231 and 233, respectively, whereby the auxiliary switches may be set to operate at predetermined desired points in the operation of the main circuit breaker 7. The operating shaft 231 of the auxiliary switch device 225 is connected by a crank 235 and link 237 to the projection 239

of an auxiliary switch operating lever 241. The lever 241 is pivotally mounted on the fixed pivot pin 53 and the free end of this lever is connected by a slot 243 to the pivot pin 49 which connects the circuit breaker operating rod 25 to the operating lever 35. The operating shaft 233 of the auxiliary switch device 227 is also connected, by a crank 245 and a link 247, to the projection 239 of the auxiliary switch operating lever 241. Thus each of the auxiliary switch devices 225 and 227 is operated by and in accordance with the movement of the circuit breaker 7.

Referring now to Fig. 3 which diagrammatically shows the circuits for electrically controlling the inlet valve electromagnet 117 and the trip device 81. 251 and 253 designate a pair of supply conductors connected to a source of electric energy (not shown). The winding 165 of the electromagnet 117 which controls the admission of compressed air to the operating cylinder for closing the circuit breaker, is connected in an energizing circuit 255 extending from the supply conductor 251, through the winding 165 of the electromagnet 117, through back contacts 257 of a release relay 259 and front contacts 261 of an operating relay 263 to the supply conductor 253. The energizing winding of the operating relay 263 is connected in an energizing circuit which extends from the supply conductor 253, through a conductor 265, back contacts 267 of the release relay 259, energizing winding of the operating relay 263, conductor 269, and through a manual control switch 271 for controlling normal closing operation of the circuit breaker, to the supply conductor 251. The energizing winding of the release relay 259 is connected in an energizing circuit which extends from the supply conductor 253, through an auxiliary switch 273 which is adapted to be closed when the circuit breaker reaches closed position, through a conductor 275, energizing winding of the release relay 259, conductor 271, through the front contacts 278 of the operating relay 263 and through a conductor 279 to the supply conductor 251.

A stick circuit is provided for maintaining the operating relay 263 energized after a momentary operation of the manual closing control switch 271. This stick circuit extends from the supply conductor 253, through the conductor 265 and back contacts 267 of the release relay 259, energizing winding of the operating relay 263, and through a conductor 283, conductor 271, front contacts 278 of the operating relay, and conductor 279 to the supply conductor 251. A locking circuit is also provided for maintaining the release relay 259 energized until the manual closing control switch 271 has been opened. This locking circuit for the relay 259 extends from the supply conductor 253, through a portion of the conductor 265, front contacts 285 of the release relay 259, energizing winding of release relay 259, conductor 283, conductor 269 and the manual closing control switch 271 to the supply conductor 251.

The winding 85 of the trip device 81 is connected in an energizing circuit which extends from the supply conductor 253, through conductor 287, through an auxiliary switch 289 which is closed when the circuit breaker is closed, conductor 291, energizing winding 85 of the trip device 81, conductor 293 and the contacts 295 of a fault responsive relay 291, and through a conductor 299 to the opposite supply conductor 251. The fault responsive relay 291 is arranged to be operated to close its contacts 295 upon the

occurrence of a predetermined overload, such, for example, as a short circuit in the main circuit 13 controlled by the circuit breaker 7. For this purpose, the energizing winding of the protective relay 297 is arranged to be energized by a current transformer 301 associated with the main circuit conductor 13. Thus when a predetermined overload condition or short circuit occurs in the main circuit 13 controlled by the breaker 7, the fault responsive relay 297 becomes energized a sufficient amount to close its contacts, thereby effecting energization of the trip device 81. When the trip device 81 is energized, it causes release of the latching means 51, 71, and circuit breaker operating lever 35, whereupon the circuit breaker is quickly moved to open position by its biasing springs.

The circuit breaker 7 may also be tripped open manually by means of a manually operable trip control switch 303 connected in series with a conductor 305 which is arranged to shunt the contacts 295 of the protective relay 297.

The circuit breaker 7 is adapted to be quickly automatically reclosed immediately following interruption of the circuit by the circuit breaker 7, through the agency of a reclosing relay 307. Automatic reclosing movement of the circuit breaker is preferably initiated immediately after the circuit breaker has interrupted the circuit and before the circuit breaker reaches full open position. Reclosing relay 307 has its contacts 309 connected in series with a conductor 311 which is connected in shunt relation to the contacts of the manual closing control switch 271. A manually operable switch 313 is provided in the conductor 311 for the purpose of preventing quick automatic reclosing operation of the circuit breaker if automatic reclosing is not desired. The energizing winding of the reclosing relay 307 is connected in series in an energizing circuit 315 which extends from the supply conductor 253, through the winding of the reclosing relay 307, through an adjustable auxiliary switch 317 which is adjusted to close during the initial opening movement of the circuit breaker, and through contacts 319 of the protective relay 297, and conductor 299 to the opposite supply conductor 251.

The operation of the mechanism is as follows, assuming the circuit breaker to be in closed position, as shown in Figs. 1 and 3. When a predetermined overload or short circuit occurs in the main circuit 13 controlled by the circuit breaker 7, the fault responsive relay 297 is immediately energized and closes its contacts 295 to effect energization of the trip device 81. When the trip device 81 is thus energized, it moves the trip plunger 79 upwardly to cause the auxiliary latch 67 to release the main latch 51, thereby releasing the breaker operating lever 35. The circuit breaker is immediately moved to open position by its biasing spring 15. The operation of the trip plunger 79 also opens the pilot valve 203, thereby causing the main exhaust valve 189 to be opened and quickly exhaust any air pressure in the operating cylinder 29, if there is any pressure in the cylinder 29 at this time. The main circuit 13 is interrupted during the first part of the opening movement of the circuit breaker 7 by the time the circuit breaker has opened through only a part of its full open distance.

Assuming the manual switch 313 to be closed, quick automatic reclosing operation of the circuit breaker will be caused to take place as soon as the circuit breaker has opened through a pre-

determined distance, less than the full open distance. Quick automatic reclosing operation of the circuit is accomplished by the reclosing relay 307 in response to closing of its circuit by the contacts 319 of the fault responsive relay 297 and closing the adjustable auxiliary switch 317. The contacts 319 of the fault responsive relay are closed simultaneously with the contacts 295 upon operation of the fault responsive relay in response to an overload or short circuit, thus immediately preparing the energizing circuit for the reclosing relay 307. During the initial opening movement of the circuit breaker, the auxiliary switch 317 closes and completes the energizing circuit for the reclosing relay 307, and the relay 307 thereupon closes its contacts 309, completing an energizing circuit for the operating relay 263, this energizing circuit extending from the supply conductor 251, through the contacts 309 of the reclosing relay, conductor 311, conductor 269, energizing winding of operating relay 263, back contacts 267 of the release relay 259, and conductor 265 to the opposite supply conductor 253. The operating relay instantly closes its contacts 278 and 281. Closing of the operating relay contacts 281 completes an energizing circuit for the inlet valve controlling electromagnet 117, through the back contacts 287 of the release relay, and through conductor 253. The electromagnet 117 when energized opens the pilot valve 151, thereby causing opening of the main inlet valve 127. Compressed air is thereupon admitted to the upper end of the operating cylinder 29 quickly reversing the opening movement and moving the operating piston 103 downwardly to reclose the circuit breaker. These operations occur substantially instantaneously so that reclosing movement of the operating piston is initiated immediately after the circuit has been interrupted and before the breaker reaches the full open position. The position at which automatic reclosing movement of the main operating piston 103 takes place is indicated by the dotted lines R in Fig. 1. As has previously been explained, the exhaust ports 181 are located in a position such that they are closed by the operating piston 103 during the first part of the opening movement of the breaker before the piston reaches the position at which compressed air is admitted for quick reclosure, so that dumping of the reclosing air is thereby prevented and the exhaust valve 189 is given a time interval to mechanically close before the downward movement of the operating piston opens the exhaust ports 181.

Closing of the contacts 278 of the operating relay 263 prepares an energizing circuit for the release relay 259. This circuit extending from the supply conductor 251, through conductor 279, contacts 278, conductor 277, energizing winding of the release relay 259, conductor 275 to the auxiliary switch 273 which closes the instant the circuit breaker reaches closed position. As soon as the circuit breaker reaches closed position, the auxiliary switch 273 completes the energizing circuit for the release relay 259, whereupon the release relay operates to open its back contacts 267 and 257 and closes its front contacts 285. The opening of contacts 257 effects deenergization of the inlet valve controlling electromagnet 117, thereby causing shutting off the supply of compressed air to the operating cylinder 29, and the opening of contacts 267 effects deenergization of the operating relay 263. The closing of the front contacts 285 normally produces no effect during quick automatic reclosing operation,

since the contacts 309 of the reclosing relay open before the breaker reaches closed position.

If the condition which caused the overload or short circuit has been removed by the time the circuit breaker completes the circuit upon a quick automatic reclosing operation, the circuit breaker remains closed and the control circuits assume the normal condition shown in Fig. 3. However, if the fault condition which causes the overload or short circuit is still present at the time the circuit is completed by the contacts of the circuit breaker during a quick reclosing operation thereof, the fault responsive relay 297 is again energized the instant the main circuit is completed again causing energization of the trip device 81. Consequently trip plunger 79 is again operated upwardly opening the pilot valve 203, thereby causing the air pressure in the operating cylinder 29 to open the main exhaust valve 189 and quickly cause collapse of the air pressure in the operating cylinder 29 even though the main inlet valve 127 may still be open at this time. The trip device 81 also moves the latches to released position. Thus the circuit breaker is caused to quickly reverse its movement and start opening even though the inlet valve may be open at this time. The opening movement of the circuit breaker is substantially unretarded due to the quick collapse of air pressure in the operating cylinder 29. A lockout device 321 of any conventional construction may be provided in the circuit of the reclosing relay 307 to prevent more than one attempted quick automatic reclosing operation of the circuit breaker, or to open the quick reclosing circuit and transfer control of the reclosing relay to a time delayed reclosing device in a manner well known in the art. If the lockout device 321 is of a character to provide for only a single quick automatic reclosure of the circuit breaker, the circuit breaker proceeds to the full open position and remains open after one unsuccessful attempt at quick reclosure.

Normal closing operation of the circuit breaker from the full open position is accomplished by closing the manual control switch 271. The closing of this switch completes an energizing circuit for the operating relay 263. When the operating relay is thus energized, it closes its contacts 261 and 278, the closing of contacts 261 completing an energizing circuit for the inlet valve controlling electromagnet 117, thereby causing compressed air to be admitted to the operating cylinder to close the circuit breaker. The contacts 278 prepare an energizing circuit for the release relay 259, this circuit being completed by the auxiliary switch 273 when the breaker reaches the fully closed position. The manual closing control switch 271 need only be closed for an instant because as soon as the operating relay closes its contacts 278, a stick circuit is completed for maintaining the operating relay energized until the release relay operates. This stick circuit has been previously described. Closing of the contacts 278 of the operating relay 263 prepares an energizing circuit for the release relay 259 which is completed by the auxiliary switch 273 when the breaker reaches the fully closed position. When the release relay 259 is energized, it opens its back contacts 257 and 261, thereby deenergizing the inlet valve controlling electromagnet 117 by the contacts 257 and also deenergizing the operating relay 263 by the contacts 261 and preventing further energization of the operating relay as long as these contacts remain open. The operation of the release relay also closes its front contacts 285

to complete a locking circuit for maintaining the release relay energized as long as the manual closing control switch 271 is held closed, this locking circuit extending from the supply conductor 253, through the front contacts 285 and energizing winding of the release relay 259, conductor 283, conductor 269 and manual closing control switch 271 to the supply conductor 251. This locking circuit thus prevents the circuit breaker from pumping if the breaker will not remain closed and the manual control switch is held in closed position. If the circuit breaker should be closed against an overload or short circuit during a normal closing operation, the trip device 81 will be operated to release the latch and cause opening of the exhaust valve so that the breaker will immediately open even though the inlet valve 189 may be open at the time the circuit is completed.

The circuit breaker may be manually tripped open by closing the manual trip control switch 303 which effects energization of the trip device 81 and tripping of the circuit breaker.

The circuit breaker operating mechanism and its electrical control as thus far described in detail above are similar to that disclosed in the aforementioned copending application of James M. Cumming and Richard C. Cunningham, Serial No. 410,686.

The combination of air pressure and operating piston diameter required to quickly reverse the switching movement and quickly automatically reclose the breaker after interruption of the circuit, and before the breaker reaches full open position, produces an operating force which is much greater than that required for normal closing operations where the breaker is closed from a position at rest in the full open position. Consequently, the extra large force required for quick automatic reclosing may cause destructive slamming of the breaker on normal closing operations. In accordance with one embodiment of the present invention, the operating mechanism is provided with an automatically selective throttle which is automatically effective to throttle or reduce the air pressure applied to the operating piston on normal closing operations, but which allows the application of full air pressure to the operating piston on quick reclosing operations.

The automatically selective throttle comprises a throttle valve 325 of the gate type which is slidably mounted in an opening 327 provided therefor in the inlet valve housing 119. The opening 327 is disposed transverse to the air inlet passage 123 at a point between the main inlet valve 127 and the inlet port 125 of the operating cylinder. The upper end of the opening 327 is closed by a plate 329 secured to the top of the valve housing 119 by cap screws 331 (only one being shown). The throttle valve is slidable up or down in the opening 327 to either fully open or partially close the air inlet passage 123. A spring 333 biases the throttle valve 325 upwardly to its open or non-throttling position shown in Fig. 1. In this position, the throttle valve 325 allows full air pressure to be applied to the breaker operating piston when the main inlet valve 127 is opened to produce quick automatic reclosing of the breaker. The throttle valve is adapted to be moved downwardly to a predetermined partially closed or throttling position, as shown in Fig. 4, by a small piston 335 which is movable in a cylinder 337 formed in the valve housing 119. In the partially closed or throttling position, as shown in Fig. 4, the throttle valve acts to restrict or reduce the air pressure applied to the breaker operating piston 103 on

normal closing operations. The piston 335 is directly connected by a rod 339 to the throttle valve 325, and the valve biasing spring 333 is a helical compression spring disposed in the lower portion of the cylinder 337 between the bottom of the piston 335 and a closure plug 341 threaded into the lower end of the cylinder 337. An adjustable screw 343 extending upwardly through the closure plug 341 is provided for adjusting the degree of throttling to be produced by the throttle valve 325 on normal closing operations of the breaker.

The throttle valve is adapted to be automatically controlled in accordance with the position of the breaker operating piston 103 at the time the main inlet valve 127 is opened, so that the throttle valve will remain in full open position on a quick automatic reclosing operation where the reclosing movement is initiated when the breaker is only partly open and the operating piston is in a position such as indicated by the dotted lines represented at "R" in Fig. 1, and so that the throttle valve is caused to assume and remain in throttling position, as shown in Fig. 4, on normal closing operations where the breaker is closed from the full open position starting with the operating piston in its uppermost position, as indicated by the dotted lines represented at "C" in Fig. 1. In order to thus make the throttle valve automatically selective, a pair of auxiliary air passages 345 and 347 are provided, each of which connects the main operating cylinder 29 with the throttle valve cylinder 337. The passage 345 is located adjacent the upper end of operating cylinder 29 and communicates with the upper end of the throttle valve cylinder 337 above the piston 335. The other air passage 347 is located below the passage 345 and in a position to be closed by the throttle valve piston when that piston is moved downwardly. The arrangement of the passages is such that on normal closing operations, which always start with the breaker piston 103 in its uppermost position C, as soon as the air pressure starts the downward movement of the operating piston, this piston uncovers the exhaust passage 345, as shown in Fig. 4, and consequently the air pressure is admitted through the passage 345 to the upper side of the throttle valve piston 335 and quickly moves the piston 335 downwardly, since at this time the lower portion of the throttle valve cylinder 337 below the piston 335 is open to the atmosphere because the breaker operating piston is above the air passage 347. Downward movement of the piston 335 moves the throttle valve to the throttling position shown in Fig. 4 and maintains it in such position until the air pressure is cut off, due to the fact that the piston 335 closes the air passage 347 and passes below this passage before the breaker operating piston 103 passes below the passage 347. Thus reduced air pressure is applied to the breaker operating piston 103 on all normal closing operations. When the air pressure is cut off near the end of the closing stroke, and the pressure in cylinder 29 drops, the throttle valve spring 333 returns the throttle valve to its more widely open position where it remains while the breaker is in closed position and during the next opening stroke. On a quick automatic reclosing operation, the inlet valve is opened during an intermediate portion of the opening stroke of the breaker, admitting air pressure to the operating cylinder during the opening stroke when the operating piston 103 is in a position such as indicated by the dotted lines R in Fig. 1. Under these conditions, both passages 345

and 347 are open to the high pressure, thus preventing operation of the throttle valve piston 335 since at this time the valve piston 335 is disposed above the passage 347 and below the passage 345. The small pressure differential, due to leakage through the bleeder port 349 in the valve cylinder 337, is insufficient to overcome the throttle valve biasing spring 333. Consequently, the throttle valve remains in full open position, as shown in Fig. 1, during quick automatic reclosing operations so that full air pressure is applied to the breaker operating piston. The fact that the throttle valve is in widely open position during the opening stroke makes any movement of the throttle valve unnecessary to initiate a partial stroke reclosing operation, even though the reclosing is initiated at an intermediate point in the stroke where the throttle valve would be partially closed during a normal full closing stroke.

Thus, to summarize, the throttle valve is in partially closed position during at least the early and intermediate portions of a normal full closing stroke to limit the energy imparted to the piston and contacts, but the valve is in a more widely open position during the intermediate portion of the opening stroke so that if a quick reclosing operation is then initiated, a large force is available for reversing the movement and closing the circuit breaker.

While the invention has been disclosed in accordance with the provisions of the patent statutes, it is to be understood that various changes in the structural details and arrangements of parts thereof may be made without departing from some of the essential features of the invention. It is desired, therefore, that the language of the appended claims be given the broadest reasonable construction permissible in the light of the prior art.

I claim as my invention:

1. In combination, a circuit breaker, operating mechanism for said breaker, power means for actuating said mechanism to close the breaker, said power means being operable to effect normal closing operation of the breaker and also operable to effect quick automatic reclosing operation of the breaker after the circuit is interrupted and at least by the time the breaker reaches full open position, and automatically selective means for causing a greater average closing force to be applied to said breaker on a quick automatic reclosing operation during that portion of the closing stroke traversed on quick automatic reclosing operation than during the same portion of the closing stroke on normal closing operation.
2. In combination, a circuit breaker movable to open and to closed circuit position, power operated means for actuating said breaker to closed position, said power operated means being operable to effect normal closing operation of the breaker from full open position of the breaker and also being operable to effect quick automatic reclosing operation of the breaker after interruption of the circuit and before the breaker reaches full open position, and means automatically operable to cause a greater average closing force to be applied to said breaker on a quick reclosing operation during that portion of the closing stroke traversed on quick automatic reclosing operation than during the same portion of the closing stroke on normal closing operation.
3. In combination, a circuit breaker movable to open and to closed circuit position, operating mechanism for said breaker, power means op-

erable to cause said mechanism to effect normal closing operation of the breaker from the full open position of the breaker, said power means also being operable during opening of the breaker to cause said mechanism to initiate quick automatic reclosing of the breaker at a point in the opening stroke intermediate the open and closed positions of the breaker, and means automatically operable to cause a greater average closing force to be applied to said breaker on a quick automatic reclosing operation during that portion of the closing stroke traversed on quick automatic reclosing operation than during the same portion of the closing stroke on normal closing operation.

4. In combination, a circuit breaker movable to open and to closed circuit position, operating mechanism for opening and for closing said breaker, means for causing automatic opening of said breaker in response to predetermined overload conditions in the circuit, power means operable to cause said mechanism to effect normal closing of the breaker from the full open position of the breaker, said power means also being operable during opening of the breaker to cause said mechanism to initiate quick automatic reclosing of the breaker at a point in the opening stroke intermediate the full open and closed positions of the breaker, and means automatically operable to cause said power means to apply a greater average closing force to said mechanism on a quick automatic reclosing operation during that portion of the closing stroke traversed on quick automatic reclosing operation than during the same portion of the closing stroke on normal closing operation.

5. In combination, a circuit breaker movable to open and to closed circuit position, operating mechanism for opening and for closing said breaker, means operable to cause opening of the breaker in response to predetermined overload conditions in the circuit, power means operable during opening of the breaker to apply a closing force to said mechanism to initiate quick automatic reclosing of the breaker before the breaker reaches full open position, said power means also being operable to cause said mechanism to effect normal closing of the breaker from the full open position thereof, and means automatically operable to reduce the average closing force applied to said breaker on normal closing operations during that portion of the closing stroke which constitutes the total closing stroke that is traversed during a quick automatic reclosing operation.

6. In combination, a circuit breaker movable to open and to closed circuit position, fluid pressure operated means for closing said breaker, a source of fluid under pressure, means including a valve operable to connect said fluid pressure operated means to said source of fluid pressure to close the breaker, means for operating said valve to effect normal closing operation of the breaker, and means for operating said valve to effect quick automatic reclosing operation of the breaker after the circuit is interrupted and at least by the time the breaker reaches open position, and means for automatically varying the flow of fluid to said fluid pressure operated means, said means for varying the flow of fluid being operable to reduce the average fluid pressure applied to said fluid operated means on normal closing operations as compared to the average fluid pressure applied during quick automatic reclosing operations.

7. In combination, a circuit breaker movable to open and to closed circuit position, fluid pressure operated means for closing said breaker, a source of fluid under pressure, means including a valve for connecting said fluid pressure operated means to said source of fluid pressure to close the breaker, means for operating said valve to effect normal closing operation of the breaker from the full open position, and means for operating said valve to effect quick automatic reclosing of the breaker after interruption of the circuit and before the breaker reaches full open position, and means comprising a throttle means operable to reduce the fluid pressure applied to said fluid operated means during at least a substantial portion of the closing stroke on normal closing operations, said means comprising said throttle means being ineffective to reduce the fluid pressure applied to said fluid pressure operated means on quick automatic reclosing operations.

8. In combination, a circuit breaker movable to open and to closed circuit position, fluid pressure operated means operable to close the breaker, means to cause opening of the breaker in response to predetermined overload conditions, a source of fluid under pressure, means including a valve operable to connect said fluid pressure operated means to said source of fluid pressure to close the breaker, means for operating said valve to effect a normal closing operation of the breaker from the full open position of the breaker, means for operating said valve to effect quick automatic reclosing operation of the breaker during opening of the breaker before said breaker reaches full open position, and means automatically operable to cause a greater fluid pressure to be applied to said fluid pressure operated means on quick automatic reclosing operations than during a portion of the closing stroke on normal closing operations.

9. In combination, a circuit breaker movable to open and to closed circuit position, fluid pressure operated means operable to move the breaker to closed position, means operable to cause opening of the breaker in response to predetermined overload conditions in the circuit, a source of fluid under pressure, means including variable orifice valve means operable to connect said fluid pressure operated means to said source of fluid pressure to close the breaker, means for operating said valve means to effect normal closing operation of the breaker from the full open position of the breaker, means for operating said valve means to initiate quick automatic reclosing operation of the breaker during opening thereof, and said valve means being operable in response to a quick automatic reclosing operation to cause a greater rate of fluid flow to said fluid pressure operated means on quick reclosing operations thereof than during at least a portion of the closing stroke on normal closing operations.

10. In combination, a circuit breaker movable to open and to closed circuit position, fluid pressure operated means for moving the breaker to closed position, means for biasing said breaker to open position, latching means for holding said breaker closed, tripping means operable to cause said latching means to release the breaker and thereby cause opening of the breaker, a source of fluid under pressure, means including a valve operable to connect said fluid pressure operated means to said source of fluid pressure to close the breaker, means for operating said valve to effect normal closing operation of the breaker from the full open position, means for operating said valve

to effect the initiation of quick automatic reclosing operation of the breaker during the opening stroke before the breaker reaches full open position, and means automatically operable to cause greater fluid pressure to be applied to said fluid pressure operated means on quick reclosing operations of the breaker than during a portion of the closing stroke on normal closing operations.

11. In combination, a circuit breaker movable to open and to closed circuit position, fluid pressure operated means for moving said breaker to closed position, means operable to cause opening of the breaker in response to predetermined overload conditions in the circuit, a source of fluid under pressure, means including a valve for connecting said fluid pressure operated means to said source of fluid pressure to close the breaker, means for operating said valve to effect normal closing operation of the breaker from the full open position, means for operating said valve to effect the initiation of quick automatic reclosing operation of the breaker during the opening stroke thereof before the breaker reaches full open position, and means for automatically varying the flow of fluid under pressure to said fluid pressure operated means, said means for varying the flow of fluid being operable to cause greater fluid pressure to be applied to said fluid pressure operated means on quick automatic reclosing operations than during at least a portion of the closing stroke on normal closing operations.

12. In combination, a circuit breaker movable to open and to closed circuit position, fluid pressure operated means for moving said breaker to closed position, means operable to cause opening of the breaker in response to predetermined overload conditions in the circuit, a source of fluid under pressure, means including a valve for connecting said fluid pressure operated means to said source of fluid pressure to close the breaker, means for operating said valve to effect normal closing operation of the breaker from the full open position, means for operating said valve to effect the initiation of quick automatic reclosing operation of the breaker during the opening stroke thereof before the breaker reaches full open position, and means comprising an automatically operable throttle valve operable to reduce the fluid pressure applied to said fluid pressure operated means on normal closing operations.

13. In combination, a circuit breaker movable to open and to closed circuit position, operating mechanism therefor comprising an operating cylinder, a piston in said cylinder for moving said breaker to closed position, a source of air under pressure, means including a valve operable to connect one end of said cylinder to said source of air under pressure to close the breaker, means operable in response to the occurrence of predetermined overload conditions in the circuit to cause opening of the breaker, means for operating said valve to effect a normal closing operation of the breaker from the full open position, means for operating said valve to effect the initiation of quick automatic reclosing operation of the breaker during the opening stroke of the breaker before the breaker reaches full open position, and means automatically operable to cause greater air pressure to be applied to said operating piston on quick automatic reclosing operation than during at least a portion of the closing stroke on normal closing operations.

14. In combination, a circuit breaker movable to open and to closed circuit position, operating mechanism therefor comprising an operating cyl-

inder, a piston in said cylinder for moving said breaker to closed position, a source of air under pressure, means including a valve operable to connect one end of said cylinder to said source of air under pressure to close the breaker, means operable in response to the occurrence of predetermined overload conditions in the circuit to cause opening of the breaker, means for operating said valve to effect a normal closing operation of the breaker from the full open position, means for operating said valve to effect the initiation of quick automatic reclosing operation of the breaker before the breaker reaches full open position, and means comprising an automatically operable throttle valve operable to automatically reduce the air pressure admitted to said cylinder on normal closing operations.

15. In combination, a circuit breaker movable to open and to closed circuit position, operating mechanism therefor comprising an operating cylinder, an operating piston in said cylinder operable to move said breaker to closed position, a source of air under pressure, means including a valve operable to connect one end of said cylinder to said source of air under pressure to cause closing of the breaker, means operable in response to predetermined overload conditions in the circuit to cause opening of the breaker, means for operating said valve to effect normal closing operation of the breaker, means for operating said valve to effect the initiation of quick automatic reclosing operation of the breaker during the opening stroke before the breaker reaches full open position, a throttle valve in the connection between said cylinder and said source of air under pressure and means for automatically causing said throttle valve to assume a predetermined throttling position during at least a portion of the closing stroke on normal closing operations and a non-throttling position on quick automatic reclosing operations of the breaker.

16. In combination, a circuit breaker movable to open and to closed circuit position, operating mechanism therefor comprising an operating cylinder, an operating piston in said cylinder operable to move the breaker to closed position, a source of air under pressure, an air inlet connection between said source of air pressure and one end of said cylinder, a valve in said connection operable to admit air under pressure into said one end of the cylinder to close the breaker, means operable in response to predetermined overload conditions in the circuit to cause opening of the breaker, means for operating said valve to effect normal closing operation of the breaker from the full open position, means for operating said valve to admit air under pressure to said end of the cylinder during the opening stroke of the breaker to initiate quick automatic reclosing operation of the breaker from a position intermediate the full open and closed position thereof, an automatically selective throttle valve in said inlet connection automatically operated by air pressure in said cylinder to reduce the air pressure applied to said operating piston on normal closing operations.

17. In combination, a circuit breaker movable to open and to closed circuit position, operating mechanism therefor comprising an operating cylinder, an operating piston in said cylinder operable to move the breaker to closed position, a source of air under pressure, an air inlet connection between said source of air pressure and one end of said cylinder, a valve in said connection

21

operable to admit air under pressure into said one end of the cylinder to close the breaker, means operable in response to predetermined overload conditions in the circuit to cause opening of the breaker, means for operating said valve to effect the normal closing operation of the breaker from the full open position, means for operating said valve to admit air under pressure to said end of the cylinder during the opening stroke of the breaker to initiate quick automatic reclosing operation of the breaker from a position intermediate the full open and closed position thereof, a throttle valve in said inlet connection, a cylinder having a piston therein connected to said throttle valve for operating said throttle valve, a spring for biasing said throttle valve to non-throttling position, and a pair of air passages connecting predetermined points of said throttle valve cylinder to predetermined points of said breaker operating cylinder to cause said throttle valve to remain in non-throttling position on quick automatic reclosing operations and to assume a throttling position to reduce the air pressure applied to said breaker operating piston on normal closing operations.

18. In combination, a circuit breaker movable to open and to closed circuit position, operating mechanism therefor comprising an operating cylinder, an operating piston in said cylinder operable to move the breaker to closed position, a source of air under pressure, an air inlet connection between said source of air pressure and one end of said cylinder, a valve in said connection operable to admit air under pressure into said one end of the cylinder to close the breaker, means operable in response to predetermined overload conditions in the circuit to cause opening of the breaker, means for operating said valve to effect normal closing operation of the breaker from the full open position, means for operating said valve to admit air under pressure to said end of the cylinder during the opening stroke of the breaker to initiate quick automatic reclosing operation of the breaker from a position intermediate the full open and closed position thereof, an automatically selective throttle valve in said inlet connection, a cylinder having a piston therein connected to said throttle valve for operating the valve, a spring for biasing said throttle valve to non-throttling position, an air passage connecting one end of said throttle valve cylinder with said one end of said operating cylinder, a second air passage communicating at one end with the throttle valve cylinder at a point which is on the other side of the throttle valve piston from said first passage when said throttle valve is in non-throttling position, said second passage communicating at its other end with said breaker operating cylinder at a point such that it is closed by said breaker operating piston when the breaker is in full open position, said throttle valve remaining in non-throttling position on quick automatic reclosing operations of the breaker and being moved to a throttling position to reduce air pressure applied to the breaker operating piston on normal closing operations.

19. In combination, a circuit breaker having relatively movable contacts, a fluid motor operatively related to the movable contact, a source of fluid under pressure, a connection including control valve means for admitting fluid from said source to said motor to cause closing operation of the breaker, and means for operating said control valve means to restrict flow of fluid to the fluid motor during at least an early part of full

22

strokes of the fluid motor in closing the breaker and to permit a greater flow of fluid during at least the latter portion of said early part of the stroke upon partial strokes of the fluid motor in closing the breaker.

20. In combination, a circuit breaker having relatively movable contacts, operating means therefor comprising an operating cylinder, an operating piston in said cylinder operatively related to the movable contact, a source of fluid under pressure connected to said cylinder, control valve means in said connection for admitting fluid from said source to said cylinder to cause said piston to effect closing of said circuit breaker, and means for automatically operating said control valve means to vary the flow of fluid to said cylinder in accordance with whether said piston makes a full or a partial closing stroke.

21. In combination, a circuit breaker having relatively movable contacts, a fluid motor comprising a cylinder and an operating piston therein operatively related to the movable contact, a source of fluid under pressure, means interconnecting the motor to said source for closing the circuit breaker, a control valve in said interconnecting means operable to admit fluid from said source to said motor to effect closing operation of the breaker, and variable orifice means interposed in said interconnecting means controlled in accordance with whether said operating piston makes a full or a partial closing stroke for varying the flow of fluid to said cylinder to vary the closing force applied to the piston.

22. In an electric circuit breaker comprising a plurality of relatively movable contacts, a fluid motor including a piston for producing relative movement between said contacts, a source of fluid under pressure, means for interconnecting said source and said fluid motor, and fluid actuated valve means for varying the flow of fluid between said source and said fluid motor during an operating stroke of said circuit breaker, said fluid actuated valve means including a second piston and means for controlling the flow of fluid which actuates said second piston in response to the operating stroke of the circuit breaker, and said fluid motor being so constructed and arranged with reference to said fluid actuated valve means as to permit said fluid under pressure to act initially on substantially the entire working face of said piston of the fluid motor.

23. In an electric circuit breaker comprising a pair of relatively movable contacts, a fluid motor having a piston for operating said circuit breaker, a source of fluid under pressure, means including a main valve for controlling the flow of fluid between said source and said motor to produce relative movement between said contacts, fluid actuated throttle valve means interposed between said main valve and said fluid motor, and one or more fluid passages extending from said fluid motor to said fluid actuated throttle valve for actuating the throttle valve in response to movement of said piston with respect to said one or more fluid passages and said actuation of the throttle valve varying the amount of fluid supplied to the fluid motor during the time said fluid motor produces relative movement between said contacts, said fluid actuated throttle valve means being incapable of transmitting substantially any force from said fluid under pressure acting thereon to said fluid motor.

24. In an electric circuit breaker comprising a plurality of relatively movable contacts, a fluid

23

motor including a cylinder and a piston for producing relative movement between said contacts, a source of fluid under pressure, means for interconnecting said source and said fluid motor for closing said circuit breaker, one or more fluid passages opening into the side wall of said cylinder and means interposed between said source and said fluid motor and actuated in response to movement of said piston across said one or more fluid passages for preventing excessive acceleration of the movable parts of said circuit breaker during the initial part of the closing operation, said fluid motor being so constructed and arranged with reference to said last-mentioned means as to permit said fluid under pressure to act initially on substantially the entire working face of said piston.

25. In a fluid-actuated electric circuit breaker comprising a plurality of relatively movable con-

24

5 tacts, a fluid motor for producing relative movement between said contacts, a source of fluid under pressure, means for interconnecting said source and said fluid motor for closing said circuit breaker, and a variable orifice means interposed between said source and said fluid motor, means causing said variable orifice means to be partially closed during at least an early part of the closing stroke of said contacts to restrict the 10 flow of fluid to the fluid motor for preventing excessive acceleration of the movable parts of said circuit breaker during the closing operation thereof, and said means causing said variable orifice means to be more widely open during an intermediate portion of the opening stroke than the orifice is open during the corresponding intermediate portion of the closing stroke.
